(57) **CLAIM**

We claim the ornamental design for a cosmetic applicator, as shown and described.

DESCRIPTION

FIG. 1 is a top perspective view of a cosmetic applicator showing our new design;

FIG. 2 is a rear perspective view of FIG. 1;

FIG. 3 is the side elevational view of FIG. 1;

FIG. 4 is a front elevational view of FIG. 1;

FIG. 5 is a top plan view of FIG. 1; and,

FIG. 6 is a bottom plan view FIG. 1.
